[57] CLAIM

The ornamental design for a table, as shown and described.

DESCRIPTION

FIG. 1 is a front elevational view of a table showing my new design; the rear elevational view being identical thereto; FIG. 2 is a right side elevational view, the left side elevational view being identical;

FIG. 3 is a top plan view thereof;

FIG. 4 is a bottom plan view thereof;

FIG. 5 is a front elevational view of a second embodiment of the table shown in FIG. 1;

FIG. 6 is a left side elevational view thereof, with the right side elevational view being a mirror image;

FIG. 7 is a rear elevational view thereof;

FIG. 8 is a top plan view thereof;

FIG. 9 is a bottom plan view thereof;

FIG. 10 is a front elevational view of a third embodiment of the table shown in FIG. 1;

FIG. 11 is a left side elevational view thereof, with the right side elevational view being a mirror image;

FIG. 12 is a rear elevational view thereof;

FIG. 13 is a top plan view thereof;

FIG. 14 is a bottom plan view thereof;

FIG. 15 is a front elevational view of a fourth embodiment of the table shown in FIG. 1; the rear elevational view being identical thereto;

FIG. 16 is a left side elevational view, the right side elevational view being identical thereto;

FIG. 17 is a top plan view thereof; and,

FIG. 18 is a bottom plan view thereof.
